MECHANICAL VIBRATOR SYSTEM

Philip F. Scofield, Palo Alto, Calif., assignor to
 Heintz & Kaufman, Ltd., San Francisco, Calif.,
 a corporation of Nevada

Application January 2, 1934, Serial No. 705,039

6 Claims. (Cl. 200—19)

My invention relates to a mechanical vibrator and means and method of operation, with particular reference to a vibrator having enclosed contacts operated by a cyclical shaking.

5 Among the objects of my invention are: to provide a mechanical vibrator wherein contact points are protected from excessive arcing; to provide a mechanical vibrator wherein contacts are surrounded by a substantially oxygen free 10 atmosphere; to provide a mechanical vibrator wherein the contacts are enclosed in a vitreous envelope; to provide a mechanical vibrator having a movable contact adapted to be mechanically shaken to alternately touch stationary contacts; to provide a mechanical vibrator wherein a movable contact is adapted to alternately touch 15 stationary contacts, the movable contact being supported by a member deformable beyond the elastic limit of the supporting material within 20 its range of motion; to provide a means and method of generating or rectifying alternating current by the use of a mechanical vibrator; to provide a mechanical vibrator assembly enclosed within a vitreous envelope; and to provide a combination of a vibrator contact assembly enclosed 25 within a vitreous envelope with mechanical means external of said envelope for shaking the assembly to produce alternating current generation or rectification.

30 Other objects of my invention will be apparent or will be specifically pointed out in the description forming a part of this specification, but I do not limit myself to the embodiment of the invention herein described, as various forms may 35 be adopted within the scope of the claims.

This application deals only with the combination of enclosed contacts with their means for shaking. The circuits which are herein shown but not claimed are the subject of my application entitled "Vibrator and circuit therefor", Serial No. 713,123, filed February 27, 1934.

In the drawings which illustrate a preferred embodiment of my contact assembly, together with several embodiments of a means for shaking 45 one or more of the contact assemblies:

Figure 1 is a longitudinal sectional view of a contact assembly tube.

Figure 2 is a longitudinal sectional view of the same tube taken along a plane at right angles 50 to that of Figure 1, taken as indicated by the line 2—2 in Figure 1.

Figure 3 is a cross sectional view taken as indicated by the line 3—3 in Figure 2.

Figure 4 is a side view in elevation of a single 55 tube, together with its shaking mechanism.

Figure 5 is a top view, somewhat diagrammatical, of the arrangement used to operate two tubes simultaneously.

Figure 6 is a top view, also diagrammatical, of the linkage used to operate three tubes for three phase rectification or generation.

Figure 7 is a circuit, diagrammatical and reduced to lowest terms, wherein my tube may be used to generate alternating current from a direct current source.

With the increasing popular use of low powered radio receiving and transmitting sets, particularly those adapted for operation at extremely high frequencies, the problem of high voltage 10 D. C. for plate supply has become increasingly 15 important. Dry batteries do not last long under transmitting loads. Furthermore, these new radio sets are so light in relation to their range that they are used, to a large extent, as portable equipment. They are also installed in places 20 where alternating current is not easily available. Automobiles, small boats, airplanes and ships of any size are examples of locations where alternating current is not easily available.

It is, of course, possible to install motor generators in such places, or dynamotors. These machines are expensive and often times inefficient and wasteful of power.

There has been, recently, a trend toward mechanical vibrators for the cyclical chopping of 30 direct currents so that the resultant alternating current may be used, either before or after voltage step-up, for transmitting and receiving sets. It has been customary, however, to use vibrators of the tuned reed type operating in air, and 35 the reed has usually been electrically oscillated. Considerable trouble, however, has been encountered with tuned reed vibrators. They are prone to arc, but to my mind their greatest drawback is their tendency to bounce upon making 40 contact. This proclivity is due to the resonant suspension of the moving contact, and the bouncing gives rise not only to serious arcing and consequent wear of the contacts but also to vagaries in wave form, and in many cases to the 45 generation of interference. A positive electrical contact is highly to be desired in a mechanical vibrator, together with a clean break. Any hesitation, either at the making or breaking, will not only cause noise in the form of audio frequency 50 sputtering, but will also cause an arc which, in cooperation with associated circuits, may easily set up undesirable high frequency oscillations.

Still another objection to tuned reed vibrators is that their period of vibration changes with 55

temperature. They are also subject to operational disturbance when used in moving vehicles having various periods of vibration of their own, which may be transmitted to the reed, or when 5 such vehicles encounter bumps.

The mechanical vibrating system of my invention is not subject to the difficulties as described above, and the apparatus comprises, in broad terms, the combination of a pair of spaced stationary contacts and a movable contact supported 10 between the stationary contacts. I prefer to mount the movable contact on a soft metal support and have the range of motion of the movable contact sufficient that the support is deformed 15 during the passage from one contact to the other, the deformation being beyond the elastic limit of the material. Therefore the movable contact and stationary contact, when they are in touching position, are held tightly together by the 20 strength of the metal, thereby preventing bounce. The motion of the movable contact is preferably caused by a mechanical shaker, a reciprocating motion being applied in line with the path of the movable contact, this motion being cyclical and 25 of course of sufficient strength to overcome the elastic force tending to hold the movable contact touching the stationary contact. In order to further safeguard the operation of the device, I prefer to mount the entire contact assembly in 30 a vitreous envelope and to operate the contacts in a space substantially free from oxygen. The preferred method of doing this is to evacuate the envelope and either leave it in an evacuated condition or to refill the envelope with an inert gas. 35 A better understanding of my vibrator system may be had by reference to the figures wherein an envelope 1, preferably cylindrical in shape, is provided with a reentrant stem 2 having a pinch 3 on its inner end. The entire tube stem and pinch 40 are quite similar in their preferred form to the envelopes commonly used in the construction of thermionic tubes, in fact the entire contact assembly tube may be made on machines adapted to produce vacuum tubes. The pinch 3 has 45 sealed therethrough a pair of stationary contact supports 4-4. While the actual shape of the section of these supports is immaterial as long as they are exceptionally stiff so as to be non-vibrating, I prefer to form them as shown of 50 strong T section, with their bases thoroughly imbedded in, or even passing through, the pinch. Stationary contact leads 5 are extended from the supports 4-4 to facilitate outside connections. The length of the portion of the supports 4-4 55 which extends into the inside of the tube may well be extremely short, even shorter than shown in the drawings if desired, in order that the supports 4-4 may not have any extensive vibratory periods. The outer ends 6-6 of these supports 60 carry opposed stationary contacts 7-7 spaced by the short gap.

The stationary contacts 7-7 preferably have parallel planar faces, although they may be 65 slightly beveled to compensate for the arc described by the movable contact. This movable contact 8 is positioned between the two stationary contacts and has separate faces opposing the faces of each of the stationary contacts. The movable contact is positioned on a cross bar 9. 70 This cross bar is of relatively heavy material and not substantially deformable under the forces available in the operation of the tube. Each of the opposite ends of this cross bar is welded to movable contact supports 10-10 extending toward the stem, and in the neighborhood of the 75

base of the stem, welded to a stem clamp 11. The stationary contact supports are preferably formed from a soft, easily deformable metal, and in the treatment of the tube during the pumping operation, are thoroughly annealed. I have found that soft copper forms an excellent support, as it may be continuously deformed without danger of breaking during a commercially practical life. A stationary contact lead 14 passes through the pinch 3, and is bent to follow along the stem to 1 make contact with the movable support clamp 11.

After the contacts have been assembled and mounted as described, the tube is preferably exhausted, left that way, or filled with an inert gas, the exhaust tube seal tip being designated by 1 the numeral 12.

A pivot band 15 is then placed around the outside of the tube, concentrically located with respect to the internal movable support clamp, and carries thereon trunnions 16-16. The outwardly 20 extending trunnions 16-16 have a common axis which passes through the tube at right angles to the direction of motion of the movable contact.

On the other end of the tube is positioned an operating clamp 17, substantially in the plane of 25 the contacts, and having a connection lip 18 projecting therefrom in line with the three contacts. The tube is then mounted as shown in Figure 4. The trunnions are inserted in a bearing bracket 19 with the exhaust tip pointing downwardly. The bearing bracket is held in position by an upright standard 20 attached to a suitable base 21. Also mounted on the base is a motor 22 carrying at one end a crank 23. This crank has a connecting rod 24 interconnecting the crank pin of the 30 motor with the operating lip 18 of the tube.

The device is then ready for mechanical operation. When the motor 22 is caused to rotate, the crank arm causes the contact end of the tube to oscillate back and forth on the trunnions 40 16-16. As the motion is applied in line with the path of the movable contact, the movable contact will tend to stand still as the stationary contacts are forced toward it. In order for the 45 movable contact to touch the stationary contacts, the support will be deformed, but as the material of the support is soft the deformation will be beyond the elastic limit of the material, and when the contacts touch there is no tendency for the two contacts to spring away again to 50 cause a break. The movable contact will be carried along touching the stationary contact until the direction of motion of the tube as a whole is reversed, whereupon the movable contact will leave the one stationary contact and go to the other, deforming beyond its elastic limit during its passage so that it will hold against the other contact during the return journey. I have found that this arrangement gives an exceptionally 55 clean and snappy make and break, with no tendency to bounce whatsoever.

A typical circuit which may be used with the vibrator of my invention is shown in Figure 7. In this circuit the two stationary contacts are 65 connected across an inductance 25, the inductance being shunted by a variable condenser 26. I prefer to tune this combination of inductance and capacity to the frequency desired in the output of the system, and we may take as an example 60 cycles. The inductance 25 is provided with a center lead 26' which, together with a lead 70 27 which is connected to the movable contact 8, constitutes the D. C. input to the device. Output leads 29 are extended from the terminals 75

of the inductance 25, the alternating current being obtainable therefrom. The resistances 30—30, in series with condensers 31—31, are shunted between each of the stationary contacts 5 and the movable contacts to absorb what small tendency to arc may be present. The circuit as shown is ideally adapted for use on ship board, as alternating current of approximately 160 volts may be obtained from the 100—110 volt D. C. ship 10 supply. In use in the above described circuit the motor speed is regulated to give the proper number of contacts per second, i. e., 60 complete cycles per second.

In Figure 5, two of the contact tubes are shown 15 attached to a single motor being simultaneously reciprocated in opposite directions. Such a connection is ideal where it is desired that one of the two contact tubes generate alternating current to energize a step up transformer. The other of the contact tubes may then be used to rectify the stepped up current. As the two contact tubes are connected to the same shaking source, the rectifier is always in synchronism with the generator. The circuits used with this type 20 of vibrator system, and others, are fully disclosed and described in the application above referred to.

Figure 6 shows three of the contact tubes arranged to generate or rectify three phase alternating currents. It should be pointed out in this 25 respect that the same general type of motor may be used as is shown in Figure 5, with three tubes on each crank arm whereby the simultaneous rectification and generation of three phase currents may be accomplished.

While I have shown the use of a motor rotating a crank arm to give a reciprocating motion to the contact assembly tube, it should be understood that any means well known in the art may 30 be used to impart the proper reciprocating motion or shaking to the tube without departing 40 from the spirit of the invention.

I claim:

1. In a mechanical vibrator system the combination of an envelope, a pair of spaced opposed 45 stationary contacts therein, inflexible supports for said contacts, a movable contact positioned between said stationary contacts, a flexible non-resonant support for said movable contact, separate leads through said envelope for all of said 50 contacts, and means for cyclically shaking said envelope to cause said movable contact to alternately touch said stationary contacts.

2. In a mechanical vibrator system the combination of an envelope, a pair of spaced opposed 55 stationary contacts therein, relatively short inflexible supports for said contacts, a movable contact positioned between said stationary contacts, a flexible, nonresonant and relatively long support for said movable contact, separate leads through said envelope for all of said contacts, and means for cyclically shaking said envelope to 60

cause said movable contact to alternately touch said stationary contacts.

3. In a mechanical vibrator system the combination of an envelope having a reentrant stem terminating in a pinch, a pair of opposed and spaced stationary contacts inflexibly supported by said pinch, a movable contact positioned between said stationary contacts, a support for said movable contact fastened to a clamp around said stem, said support being of soft metal deformable beyond the elastic limit of the metal within the range of movement of said movable contact, separate leads through said envelope for all of said supports, and means for cyclically shaking said envelope to cause said movable contact to alternately touch said stationary contacts. 10 15

4. In a mechanical vibrator system the combination of an envelope having a reentrant stem terminating in a pinch, a pair of opposed and spaced stationary contacts inflexibly supported by said pinch, a movable contact positioned between said stationary contacts, a support for said movable contact fastened to a clamp around said stem, said support being of soft metal deformable beyond the elastic limit of the metal within the range of movement of said movable contact, separate leads through said envelope for all of said supports, means for pivoting the stem end of said envelope, and means for imparting a regular reciprocating motion to the opposite end of said envelope to cause said movable contact to alternately touch said stationary contacts. 20 25 30

5. In a mechanical vibrator system the combination of an envelope having a reentrant stem terminating in a pinch, a pair of opposed and spaced stationary contacts inflexibly supported by said pinch, a movable contact positioned between said stationary contacts, a support for said movable contact fastened to a clamp around said stem, said support being of soft metal deformable beyond the elastic limit of the metal within the range of movement of said movable contact, separate leads through said envelope for all of said supports, a pivot for the stem end of said tube, the axis of the pivot being substantially in the plane of said clamp and extending at right angles to the line of motion of said movable contact, and means for cyclically reciprocating said tube on said pivot to cause said movable contact to alternately touch said stationary contacts. 35 40 45 50

6. In a mechanical vibrator system, a plurality of tubes having therein a movable contact adapted to touch a stationary contact on each side thereof, each of said movable contacts being mounted on a support deformable beyond the elastic limit of the support within the range of motion of said movable contact, and means for imparting a cyclically reciprocating motion to each of said tubes in regular succession to cause the contacts in said tubes to be made and broken in a predetermined order. 55 60

PHILIP F. SCOFIELD.
